SOCKET FOR SWITCH SIGNAL LAMPS

Robert C. Schatzman, Arlington, N. J., assignor to
Lovell-Dressel Co., Inc., Arlington, N. J., a corporation of Maine

Application December 28, 1943, Serial No. 515,991

4 Claims. (Cl. 248—310)

This invention relates to improvements in socket means for detachably mounting a switch signal lamp on the lamp standard of a hand controlled railroad switch actuating mechanism.

This invention has for an object to provide a strong, durable and yet comparatively inexpensive stamped sheet metal socket structure adapted to be affixed to a switch signal lamp base, whereby to detachably mount said lamp on the stub of the lamp standard of a switch actuating mechanism to be served thereby.

The invention has for a further object to provide a novel socket structure for the purposes stated comprising an assembly of stamped sheet metal parts adapted to provide an axially disposed endwise open socket portion having external radially extending sections, upper portions of said sections being formed to provide lamp base engaging and supporting bracket arms, and lower portions of said sections being formed to provide foot pieces; said parts including novel means for mutually securing the same one to another in unitary socket structure forming relation.

The invention has for another object to provide a stamped sheet metal socket structure, characterized as above stated, including an independent socket bushing, and means to interchangeably affix the latter within the socket structure interior, whereby the socket structure may be furnished with a selected size of bushing corresponding to and adapted to fit the particular size of lamp standard stub upon which a lamp is desired to be mounted in any given case.

Other objects of this invention, not at this time more particularly enumerated, will be understood from the following detailed description of the same.

An illustrative embodiment of this invention is shown in the accompanying drawings, in which:

Fig. 1 is an elevational view of the stamped sheet metal socket structure according to this invention, and as operatively attached to a switch signal lamp and engaged on the lamp standard stub of a switch actuating mechanism, the lamp and lamp standard and stub being shown in dotted outline; Fig. 2 is a top plan view of the stamped sheet metal socket structure; Fig. 3 is a bottom plan view of the same; Fig. 4 is a vertical cross-sectional view thereof, taken on line 4—4 in Fig. 2; and Figs. 5, 6, 7 and 8 are respectively elevational views of the several respective parts of the stamped sheet metal socket structure; Fig. 9 is a plan view of a blank from which the parts of the socket structure are produced.

Similar characters of reference are employed in the above-described views, to indicate corresponding parts.

The socket structure according to this invention comprises four substantially similar parts A, B, C and D, each of which is formed from a sheet metal blank 10 such as shown in Fig. 9. These blanks 10 are stamped out from sheet metal stock of suitable thickness, and said blanks are given a peripheral shape calculated to provide the various elements which cooperate to make up the completed socket structure as hereinafter described.

In working a blank to produce therefrom a socket structure part, the blank is bent along a longitudinal line a—a, whereby to dispose body portions 11 and 12 thereof in right angular relation, so as to form a corner wall section of the socket portion of the completed structure.

The section 13 of the blank, which extends laterally from the body portion 11 thereof, is bent along a longitudinal line b—b so as to dispose the same in exteriorly projecting right angular relation to said body portion 11. This section 13 is of such peripheral shape that its upper portion provides a bracket arm 14 having a top edge 15 disposed in a horizontal plane spaced above the plane of the top edges of said body portions 11 and 12. The free end of said bracket arm 14 is bent along a longitudinal line c—c into substantially right angular relation to the bracket arm body, thus providing an attachment lug or ear 16, for purposes to be subsequently set forth. The lower portion of the section 13 is shaped to provide a foot piece 17 having its bottom edge 18 disposed in a horizontal plane spaced below the plane of the bottom edges of said body portions 11 and 12.

The section 19 of the blank which extends laterally from the body portion 12 thereof, is bent along a longitudinal line d—d so as to dispose the same in exteriorly projecting right angular relation to said body portion 12. Said section 19 is provided at its opposite ends with clenching lugs 20 which respectively project freely beyond the top and bottom edges of the body portions 11 and 12.

The section 13 of the blank is further provided in its respective top and bottom edges, at points thereof closely adjacent to the juncture of said section 13 with the body portion 11, with indented notches 21, for purposes presently to be set forth.

The body portion 11 of the blank is provided at its top end, for projection beyond the top edge of the corner wall section formed by the angularly

related body portions 11 and 12, with stop lug elements 22, and the body portion 12 of the blank is provided at its bottom end with keeper lugs 23 formed in connection with the bottom marginal edge portions thereof; all for purposes likewise to be presently described.

To assemble the parts A, B, C and D, which have been produced from the blanks 10 in the form and manner above described, said parts are brought together so that the included angles of their corner wall sections face inwardly. When thus brought together the outwardly and laterally extending section 19 of one part will lie in a plane parallel to that of the outwardly and laterally extending section 13-14-17 of the next adjacent part, and the former will close in face to face meeting relation to the latter. To mutually secure and interlock the parts one to another as thus related, whereby to produce the unitary socket structure, the clenching lugs 20 at the upper and lower ends of the sections 19 are turned and clenched over the top and bottom edges of the adjacent sections 13-14-17, to pass transversely thereover through the notches 21 and thence downwardly over the opposite faces of the latter, thereby securely coupling adjacent parts together in immovably affixed relation one to another. When the parts are thus united in socket structure forming relation, the adjoined corner wall sections will form a socket portion containing an endwise open socket chamber of rectangular cross-section, from which socket portion radiate the laterally and exteriorly extending sections, upper portions of which provide the bracket arms 14 and lower portions of which provide the foot pieces 17.

The blanks 10 may be provided with corner wall body portions 11 and 12 of relatively different widths (as shown), so that when said blanks are formed into the socket structure parts, and said parts are assembled, a socket portion and chamber of oblong cross-sectional shape is produced. On the other hand, if desired, the blanks 10 may be provided with corner wall body portions 11 and 12 of equal width, so that when formed into the socket structure parts, and said parts are assembled, a socket portion and chamber of square cross-section is produced.

The socket structure of this invention is adapted to be affixed to the bottom of a switch signal lamp, such e. g. as shown in dotted outline in Fig. 1 and indicated by the reference character L. Said lamp L is provided with a bottom plate P having a dependent peripheral flange F. The socket structure is assembled with the lamp by engaging its bracket arms 14 with the lamp bottom plate P, so that the latter is seated on and supported by the top edges 15 of said bracket arms, while the angular attachment lugs or ears 16 are abutted against the bottom plate flange F, to which said lugs or ears 16 may be secured in any suitable manner or by any suitable means. In this manner, the socket structure is affixed in axially aligned relation to the lamp L, so as to project downwardly therefrom.

The lamp L is adapted to be mounted on the lamp standard S of a switch actuating mechanism, desired to be served thereby, by inserting the stub s of said standard in the socket chamber of the socket structure. Since, the stubs s of different lamp standards may vary in cross sectional dimensions, the socket structure of this invention is provided with an interchangeable socket bushing 24, and means to retain the lat-

ter in operative assembled relation thereto, whereby the socket structure may be standardized, but nevertheless, by means of the interchangeable socket bushing, easily and quickly adapted to fit any given size of lamp standard stub. To this end, a socket bushing 24 of desired aperture size having been selected, said bushing 24 is inserted within the interior chamber of the socket portion, until the former is stopped against the stop lug elements 22 of the socket structure, which stop lug elements have been turned down into horizontal plane to project over the socket portion interior, and thus so as to lie in the path of upward movement of the inserted bushing 24, whereby to prevent upward displacement of the bushing from operative assembled relation to the socket portion. After the bushing 24 is thus disposed within the socket portion, the keeper lugs 23 are turned inwardly over the lower end marginal portions thereof, thus fixing the bushing in place and against downward displacement.

From the above description it will be understood that the instant invention provides a socket structure for switch signal lamps of novel sheet metal construction, which is economical to produce, and yet sturdy and durable in use; the same providing the additional advantage of including an interchangeable socket bushing, whereby a standardized form of socket structure can be quickly and easily adapted to fit various sizes of lamp standard stubs.

Having now described my invention, I claim:

1. A socket structure for attachment to the bottom of a railroad switch signal or other lamp comprising an assembly of stamped sheet metal parts, each part including a socket portion bounding corner wall section, an angularly disposed lamp base engaging and supporting bracket arm section extending exteriorly from one side margin of said corner wall section, and an angularly disposed coupling section extending exteriorly from the other side margin of said corner wall section, said coupling section terminating at its ends in clenching lug elements; said parts thus characterized being assembled together with the included angles of their corner wall sections inwardly facing to enclose an axial socket chamber, the coupling section of one part being disposed in face to face meeting relation to the bracket arm section of an adjoining part, and the clenching lug elements of said coupling sections being clenched around top and bottom marginal portions of said bracket arm sections, whereby said parts are mutually secured one to another to collectively form a unitary structure.
2. A socket structure for attachment to the bottom of a railroad switch signal or other lamp comprising an assembly of stamped sheet metal parts, each part including a socket portion bounding corner wall section, an angularly disposed lamp base engaging and supporting bracket arm section extending exteriorly from one side margin of said corner wall section, and an angularly disposed coupling section extending exteriorly from the other side margin of said corner wall section, said coupling section terminating at its ends in clenching lug elements; said parts thus characterized being assembled together with the included angles of their corner wall sections inwardly facing to enclose an axial socket chamber, the coupling section of one part being disposed in face to face meeting relation to the bracket arm section of an adjoining part, and the clenching lug elements of said coupling sections being

clenched around top and bottom marginal portions of said bracket arm sections, whereby said parts are mutually secured one to another to collectively form a unitary structure; a socket bushing inserted within said socket chamber, corner wall sections of assembled parts having inturned stop lugs at upper ends thereof engageable by the upper end of said inserted bushing, and said corner wall sections also having inturned keeper lugs at lower ends thereof to engage the lower end of said inserted bushing.

3. A socket structure for attachment to the bottom of a railroad switch signal or other lamp comprising an assembly of stamped sheet metal parts, each part including a socket portion bounding a corner wall section, an angularly disposed lamp base engaging and supporting bracket arm section extending exteriorly from one side margin of said corner wall section, and an angularly disposed coupling section extending exteriorly from the other side margin of said corner wall section, said parts thus characterized being assembled together with the included angles of their corner wall sections inwardly facing to enclose an axial socket chamber, and the coupling section of one part being secured in face to face meeting relation to the bracket arm section of an adjoining part, whereby said parts are mutually secured one to another to collectively form a unitary structure.

4. A socket structure for attachment to the bottom of a railroad switch signal or other lamp comprising an assembly of stamped sheet metal parts, each part including a socket portion bounding a corner wall section, an angularly disposed lamp base engaging and supporting bracket arm section extending exteriorly from one side margin of said corner wall section, and an angularly disposed coupling section extending exteriorly from the other side margin of said corner wall section, said parts thus characterized being assembled together with the included angles of their corner wall sections inwardly facing to enclose an axial socket chamber, the coupling section of one part being secured in face to face meeting relation to the bracket arm section of an adjoining part, whereby said parts are mutually secured one to another to collectively form a unitary structure, a socket bushing inserted within said socket chamber, corner wall sections of assembled parts having inturned stop lugs at upper ends thereof engageable by the upper end of said inserted bushing, and said corner wall sections also having inturned keeper lugs at lower ends thereof to engage the lower end of said inserted bushing.

ROBERT C. SCHATZMAN.
